By his Attorney in fact.

UNITED STATES PATENT OFFICE.

WILLARD J. ANDREWS, OF ST. LOUIS, MISSOURI, ASSIGNOR OF ONE-HALF
TO JOHN URI MUSICK, OF SAME PLACE.

OVEN-DOOR FOR STOVES.

SPECIFICATION forming part of Letters Patent No. 392,485, dated November 6, 1888.

Application filed December 5, 1887. Serial No. 257,035. (No model.)

To all whom it may concern:

Be it known that I, WILLARD J. ANDREWS, a citizen of the United States, residing at St. Louis, in the State of Missouri, have invented 5
5 certain new and useful Improvements in Oven-
Doors for Stoves, of which the following is so
full, clear, and exact a description as will ena-
ble others skilled in the art to which my in-
vention appertains to make and use the same,
10 reference being had to the accompanying draw-
ings.

This invention relates to doors of that class
having their hinges at their lower edges and
their latches at the top—such, for instance, as
15 those ordinarily used as oven-doors in stoves—
and in which it is desirable that the door when
open shall stand in a horizontal plane be-
neath and opposite the opening disclosed, for
the purpose of resting the dish or pan with-
20 drawn from the oven thereupon.

The objects of the invention are to construct
a door capable of being opened slightly and
locked in such position, having hinges integral
25 with its body and provided with a sup-
porting-arm beneath, which firmly and se-
curely supports it when open, the whole to
be simple in construction, economical in manu-
facture, and effective in operation.

To this end my device consists in the con-
30 struction hereinafter described, which I con-
sider the best means of carrying out my in-
vention.

In the drawings, Figure 1 is an elevation of
a stove-door embodying my improvements.
35 Fig. 2 is a central vertical section thereof, the
door being shown open. Fig. 3 is a detail view
of a portion of one of the supporting-arms and
its hinge-bearing. Fig. 4 is a section of the
40 hinge-connection of the arm to the stove
proper. Fig. 5 is a detail perspective on an
enlarged scale of one of the supporting-arms
and its hinge.

Similar letters of reference designate similar
parts in the several figures.

45 A designates the door proper, having a han-
dle, *a*, and provided with a catch, *b*, at its
upper edge adapted to engage a notched pro-
jection, *B*, affixed to and projecting from the
50 face of the projection *B* is struck on a curve
approximately an arc of a circle, of which the

hinges of the door are at the center, and is pro-
vided with several notches, as shown, in any
one of which the catch *b* may be rested, thus
locking the door either completely closed or 55
slightly open, as desired.

At its lower edge the door is provided with
two hinges—one on each corner. As they are
of precisely the same construction, I will de-
scribe but one. The door-frame *C* has a pro-
jection or ear, *c*, preferably having rounded up-
60 per and outer face and flat lower face. Over
and around this ear is located a strap, *D*, re-
movably secured in position by screws *d* pass-
ing into the door-frame above and below the 65
ear. Within the aperture thus left is loosely
fitted a stud, *A'*, preferably cast integral with
and projecting laterally from the lower cor-
ner of the door *A*. On and about these studs
the door turns as upon hinges, and when the 70
catch *b* is in engagement with one of the notches
of the projection *B* the weight of the door is
lifted from said studs and it hangs from the
catch *b*, thus assuring the locking of the latter
within the notch it engages. Moreover, when 75
the door is open and supported in a horizon-
tal position by the arm hereinafter described
its weight rests on said arm as a fulcrum, and
it is held rigidly in position by means of the
studs *A'* bearing upwardly against the ears *c*. 80

At some distance below the lower corner of
the door are pivoted two arms, *E*. As they
are of precisely the same construction, I will
describe but one. At its lower end the arm
85 *E* is reduced, forming shoulders *e*, and having
between them a lug, *e'*, provided with pintles
*e*², extending laterally from each side thereof,
all said parts being cast integral. Over these
pintles is located a plate, *F*, constituting the
other half of the hinge, said plate being re-
90 movably secured in place by screws *f* passing
through it and into the body of the stove in
this instance. Said plate is provided with
a central aperture in its upper edge for re-
ceiving the lug *e'*, and is recessed in its rear
95 face on either side of said aperture for receiv-
ing the pintles *e*². Moreover, the shoulders
e of the arm *E* bear upon the exterior rounded
face of said plate over and above the recesses
in its rear face within which the pintles rest, 100
whereby an extremely strong and durable
hinge is formed entirely of cast metal in but

two pieces and capable of being taken apart instantly by simply removing one screw.

The body of the arm E is bent outwardly at E' for permitting it to rest flat over the lower edge of the door when the latter is closed, and at its upper end is provided with two inwardly-projecting lugs or ears, G G', the former of which is simply straight and slides normally along and against the edge of the door A. 5 The latter lug, G', however, is provided at its end which is nearest the door with a pin, g, projecting therefrom at right angles and toward the other lug, G. The door A is provided along its outer face at each vertical edge with 10 a raised portion or band, A², against which the upper inner corner of the arm E between the ears G G' slides, and said band has a groove, A³, along its inner edge, within which said pin g fits. Upon the band A², at a suitable point, is also cast a stud, A⁴. With this 15 construction, when the door is unlatched at its upper edge and turned down on its hinges, the ears G G' slide along the edges of the band A², the pin g within the groove A³, until the 20 upper end of the arm E strikes the stud A⁴, which is properly placed, and by which the door is thus supported rigidly and firmly in a horizontal position. When the door is again 25 raised to be closed, the ears slide back to the starting point, and the arm E assumes its normal position flat against the face of the stove and out of the way. To detach the arm, all 30 that is necessary is to remove the screw f, thus loosening its pivot, twist its body until the ear G is raised above the band A², and then carry it inward toward the center of the door until the pin g is disengaged from the slot A³. In this 35

manner the arms E may be removed if it is preferred to use the door without them, replaced, if desired, or substituted by new ones 40 in case they become broken.

Having now described the objects, uses, and advantages of my invention, what I believe to be new, and desire to secure by Letters Patent, and what I therefore claim, is— 45

1. The combination, with a door having a laterally-projecting stud at its lower corner and an arm hinged at one end below said door to the frame, its other end being adapted to rest beneath said door when open and support 50 it in a horizontal position, of an ear on the door-frame, beneath which said stud rests, a strap having a recess fitting loosely over said stud and ear, and means for removably securing said strap to the door-frame, substantially as described.

2. The combination, with a door hinged at its lower edge and provided along its vertical edges on its outer face with a raised band, said band having a groove along its inner edge, of an arm hinged below said door and provided at its upper end with a lug adapted 60 to slide along the outer edge of said band when the door is opened, and also with another lug having a laterally-projecting pin entering said 65 groove in the band, as and for the purposes set forth.

In testimony whereof I affix my signature in the presence of two witnesses.

WILLARD J. ANDREWS.
